TELEVISION APPARATUS AND METHOD

Le Roy J. Leishman, Los Angeles, Calif.

Application January 27, 1931, Serial No. 511,557

14 Claims. (Cl. 178—6)

This invention relates to improvements in television apparatus and, specifically, to "framing" the received image to accord with the desired relative position between the transmitted 5 image in space and the frame in, or on, which said image may appear.

The objects of this invention are to "frame" the received image so that its outlines coincide with the outlines and boundaries of the reception frame, or to produce any desired relationship between the area of the transmitted image and that of the area wherethrough, or upon which, it may be received, which may be the exact centering of the image with the receiving 10 frame, or its relative distortion if the latter be desired.

Other objects will appear as this description proceeds.

While applicable to any present known method of transmitting pictures, or images, the principle is most simply illustrated by a description of its application to the well-known scanning disc system of television.

In the drawing:

Figs. 1 and 2 show diagrammatically, the elements of a television sending and receiving scanning arrangement in which perforated discs are employed, Fig. 1 being the sending disc and Fig. 2 the receiving disc.

Fig. 3 shows a front elevation of a frame or receiving area cooperating with a special form of reception scanning disc, said frame being provided with the adjusting features of this invention, one position being shown in full lines, another position being shown in dotted lines.

Fig. 4 is a side elevation of same, partly in section, one position being shown in full lines and another position being shown in the dotted lines.

In the figures, "A", "B", "C" and "D" are the boundaries of the receiving area or "frame" of the receptor, while "a", "b", "c" and "d" are the corresponding corners of the sending frame at the originating station. "O" and "P" are connecting wires. It is herein assumed, for simplicity, that the sending and receiving instruments are electrically connected by wires, although, it is obvious that electric waves sent out from a station through the space, or the luminiferous ether, between station and receiving apparatus will produce a similar effect, if sufficiently strong, to vary the brilliancy of a light controlled by a photo-electric cell.

"H" is a scanning disc, "K" an axle to which the disc is attached and rotated by any suitable means, as motor "M". "L" is a source of illumina-

nation energized electrically and which varies in brilliancy with variation in current flow through it. The use of photo-electric cells for varying the flow of current through any suitable electrical device, responsive to changes in the intensity of light to which they are subjected, is well-known and not a part of this invention; therefore is merely mentioned to make clear the operation of the scanning discs and the movable frame.

The usual scanning disc, shown in Figs. 1 and 2, comprising a thin, circular disc "H" provided with small holes 1, 2, 3, etc., to the last hole, here numbered "20". These holes are arranged in spiral relationship, the first, "1" having a radial distance from the centre of rotation of the disc equal to "K-1 b" or "K-2 B", while the last hole, "20", has a radius equal to "K-1 d" or "K-2 D", the distance of each hole from the centre increasing from "K D" to "K B" progressively and equally by one-twentieth this distance. The angular distance apart of the holes is constant and equal to the total circumference divided by the number of holes, which, for this particular case, would be 18 degrees apart.

The scanning disc "H-2" rotates behind a thin opaque sheet, "J-2" preferably of rigid material, having an opening, or window, "Z", through it, which, in the case of a rotating disc, has the form of a sector as shown in the figures and outlined by "A", "B", "C" and "D". Behind the disc "H" is a source of light "L" which, by means of the action of a photo-electric cell, indicated at "Q", Fig. 1, changes in brilliancy in accordance with the picture or image which is being transmitted. Light passes from source "L" through the holes "1", "2", "3" etc., when one of these is traversing the open area of the window "A", "B", "C" and "D", there being one spot or ray of light from lamp "L" through a hole in disc "H" falling on, or visible through, the window area at each instant, which light corresponds in position in the received picture with the position of the hole through the scanning disc, and its relation to the image being transmitted, at the transmitting station. By running the disc at a speed which makes a revolution in about $\frac{1}{6}$ of a second, all of the holes successively pass over the window opening within that time. Hole "1" passes across the window from right to left, following the upper edge of the window as indicated by the succession of dotted holes. As hole "1" passes from the opening "A", "B", "C" and "D", at the left

edge, hole "2" enters at the right edge at a slightly less radius, traverses the width of the window at that radius, passes behind, and is obscured by the sheet in which the window "Z" is cut. Then hole "3" follows, and so, successively, do the others, the angular spacing of the holes being constant as indicated, and equal to the angle subtended by the window "A", "B", "C" and "D". By following the paths of the holes, it will be seen that the entire number covers the total area of the window, each one passing entirely across it at one radius, the next following across it at a radius which is less than that of the preceding hole by a distance equal to the diameter of the holes, so that the radius of the inner element of one is identical with that of the outer element of the next succeeding one. Thus the twenty holes scan and cover the entire area of the window, and admit light to illumine this area in varying degrees of brilliance. Of course, in practice, the number of holes exceeds twenty, being usually forty-eight or fifty.

It is obvious that only one hole can appear over the open space at any given instant and the clearness of definition depends on the number of holes which pass over the window opening within any given time.

If an image be cast through frame "a", "b", "c", "d" of sending disc "H-1" Fig. 1, the reflected light of each point, or tiny area, of the image will pass through one of the holes of disc. Since the movement of each hole covers a horizontal strip of the received picture, and the successive strips travel radially from top to bottom of the frame "a", "b", "c", "d", it is obvious that if light reflected from the unitary elements of the image passes through the holes in sending disc "H-1" and impinge on a photo-electric cell, diagrammatically indicated at "Q", the current flow from source "T" through cell "Q" over wires "O" and "P" and through lamp "L" will vary with the degree of brilliance of the spot of light passing through a hole in the disc "H-1". Hence, the spot of light from lamp "L" passing through a hole in disc "H-2" at the same instant will have a brilliancy to accord with that passing through sending disc "H-1". If disc "H-2" be similar to disc "H-1" and they are rotated at identical speeds, each spot of light through disc "H-1" is exactly reproduced by the spot through "H-2", since each tiny area of the image reflects a certain amount of light and these small areas swiftly and successively cover the entire area of the image, the exact reproduction of the image light, and shade, on unitary areas at the receiving disc, will reproduce the image. But if the position of the holes in the two discs are not identical, the image will not be centred in the receiving frame. For instance, if hole "2" of the sending disc "H-1" is passing in front of the image while hole "16" of receiving disc "H-2" is passing over the frame, the part of the image seen through hole "2" is shown in the position of hole "16" in the receiving area, so that the top of the image begins to show near the bottom of the frame.

Also, if hole "2" in the sending disc begins to enter the sending field at the left edge at the instant when hole "16" has moved half way across the receiving window, the right hand edge of the image will form near the middle of the receiving window, or frame, and only half of the image will be seen from right to left, the other half showing from the left edge to

the middle of the receiving frame. Therefore, for the image to be received in the same position as that of the transmitted image each spot of light through disc "H-2" must fall on a position corresponding with the position on which the light beam through "H-1" falls at the same instant. For this condition, it is essential that discs "H-1" and "H-2" not only be rotated at identical speeds, but the instantaneous positions of the two discs must be identical.

Various expedients have been tried to "frame" the transmitted image so that it will be properly centred in the frame, this invention constituting a novel and simple means for this purpose.

As shown, in Fig. 3, the reception scanning disc has the series of holes extended to form two complete spiral turns around axis "K" instead of a single spiral turn. This permits two spots of light to pass simultaneously through the disc. One of the spots is obscured by an opaque movable interceptor "F", in which an opening "A", "B", "C", "D" is formed of the size and configuration for the picture. Member "F" is adapted to be turned through a small angle about "K" and to be moved radially as indicated by the dotted lines, Fig. 3.

The receiving disc "H", having holes around two complete spiral turns, two pictures could be simultaneously received if disc "H" were synchronized in position with the sending disc and two receiving areas or frames were provided, one receiving the picture in the radial zone extending from hole "1" to hole "20", the second being received in the zone from hole "21" to hole "40". Obviously, by having a receiving "frame" of the size of a single picture and moving it relatively to the disc-holes or light rays, the received picture can be caught in any position in the "frame".

As shown in Figs. 3 and 4, disc "H", driven by motor "M", is supported by flat vertical member "J", through which an opening, "Z", is formed, long enough to cover the radial extent of the double spiral and considerably wider than the reception surface. In front of the disc "H" is placed flat radial member "G" adapted to move angularly about axis "K" and having a hole "X" therethrough substantially as long as the hole "Z" and subtending an angle equal to that of the hole spacing. Member "G" may be turned angularly to any position and locked there by any desired means, such as providing considerable frictional resistance to motion and moving manually. However, for ease in manipulation and accuracy of positioning, the worm "E" mounted on supporting member "J" and mating sector "N" attached to member "G" are provided whereby angular motion may be imparted to member "G".

Lying flat against member "G" is member "F" arranged for radial movement and through which is formed the sector shaped opening "A", "B", "C", "D", constituting the picture-receiving "window" or "frame".

As one practical means for moving member "F" radially and locking it in any position, the screw "R", mounted on member "G", and co-operating nut "S", fastened to member "F", are used.

Clearly, the window or frame "A", "B", "C", "D", may be moved to receive light rays from any series of holes through disc "H" beginning with any hole and ending with the succeeding

twentieth hole so that positioning the incoming light rays in the window to make the received image centre in the frame becomes simple and easy with this invention.

- 5 The lamp "L", subject to fluctuations of light in accordance with the changes in light and shade of the transmitted image, produces the received image, so that the illumination therefrom must cover the entire area of the frame 10 "A", "B", "C", "D". If the lamp is large enough, it can remain fixed in position, but in order to concentrate the light of a small lamp on the frame, it is fastened to the outer movable member "F" by a screw "W" and angle member 15 "V" as shown, so that the lamp will be moved exactly with the frame opening "A", "B", "C", "D".

A brief summation of certain features of this invention in certain aspects, includes the provision of a scanning means which directs or admits light rays in a successive sequence to a receiving area on, or in, or through which is a viewing frame for the reception or passage of light rays which produce the image, the total 20 number of the rays to form a complete image being constant for any specific reception apparatus. The scanning device is arranged to direct two simultaneous rays of light of identical intensities on the receiving area, these two simultaneous rays being separated at the receiving area by a distance equal to the span of the viewing frame measured in the same direction as that from ray to ray, which direction is substantially transverse to the direction of movement of the scanning means. Admission of two simultaneous, 25 spatially-separated light rays of identical intensities when only one instantaneous ray is required for production of the image, means that an excess of rays pass from the light-source. 30 Hence, some thereof must be obscured. The obscuring of one ray opens a path for the other ray to fall on, or pass through, the image-viewing frame, while if the second ray be obscured, the first ray will show on or in the viewing frame, but in a different position. Therefore, 35 change in position of the scanning rays, or of the image-viewing frame, will obscure certain rays and permit passage to or through the viewing frame of others, previously obscured. Since 40 for each ray obscured, another, previously obscured ray will be made visible, it is obvious that the number of visible rays is always the same but their positions may be changed relatively to the viewing frame by relative change in position 45 between the rays and the frame.

The illustrative examples and embodiments herein of this invention have depicted the scanning means interposed between the light source and the image-viewing frame. But it is obvious 50 that other positionings of the parts is possible, and they may be assembled relatively in any convenient or preferred manner, the only essential conditions being that the total number of light rays which the scanning means is able to 55 move, or control, or transmit, must exceed the number used, or required, in forming the image, and that relative change in position between the viewing frame and the light rays be possible, which relative position change will obscure some 60 of the said excess rays and permit others previously obscured, to become visible or active, in forming an image.

In general, it is understood that many variants of this invention are possible, and, in its broader 65 aspects, it is not limited to any particular con-

struction or application, as changes in the size, proportions, configurations, arrangements, assemblage, interaction, juxtaposition and mechanical relations, as well as additions, omissions, substitutions, combinations and alterations 5 of forms, parts, members and features may be made without departing from the broad spirit of this invention.

I claim as my invention:

1. In a television receiver, a scanning disc 10 having a plurality of light-directing sections disposed in a spiral having a plurality of turns; a member pivotally mounted and substantially co-axial with, parallel to and adjacent said disc, the said member having a viewing opening 15 therethrough, two of the sides whereof are substantially radial with the center of the scanning disc, said member being adjustably rotatable about its said pivotal mounting, a second member mounted on said first member adapted to be 20 adjustably moved radially of said disc and having a viewing opening therethrough adapted to partially register with the viewing opening in said first member.

2. In a television receiver, a scanning disc having a plurality of light-directing sections disposed in a spiral having a plurality of turns; a flat opaque member pivotally mounted and substantially co-axial with, parallel to and adjacent said disc, the said member having a viewing opening therethrough, two of the sides whereof are substantially radial with the center of the scanning disc, said member being adjustably rotatable about its said pivotal mounting, a second flat opaque member mounted on said 25 first member adapted to be adjustably moved radially of said disc and having a viewing opening therethrough adapted to partially register with the viewing opening in said first member, 30 said second opening having two sides substantially normal to a disc radius bisecting the said first opening.

3. In a television receiver, a scanning disc having a plurality of light-directing sections disposed in a spiral having a plurality of turns; a flat opaque member pivotally mounted and substantially co-axial with, parallel to and adjacent said disc, the said member having a viewing opening therethrough, two of the sides whereof are substantially radial with the center of the 45 scanning disc, said member being adjustably rotatable about its said pivotal mounting, a second flat opaque member mounted on said first member adapted to be adjustably moved radially of said disc and having a viewing opening there- 50 through adapted to partially register with the viewing opening in said first member, said second opening having two sides substantially normal to a disc radius bisecting the said first opening; means for moving said first opaque member angularly, and a second independent means for moving said second member radially, of the 55 said disc.

4. In a television receiver, the combination of a scanning disc having a series of openings the locus whereof is a spiral having a plurality of turns; a member having a viewing opening therethrough, and pivotally mounted adjacent to and substantially parallel and co-axial with the scanning disc, said viewing opening having 65 two sides radial of said pivotal mounting, each side having a length substantially equal to twice the turn pitch of said spiral.

5. In a television receiver, the combination of a scanning disc having a series of openings the 70

- locus whereof is a spiral having a plurality of turns; a member having a viewing opening therethrough, and pivotally mounted adjacent to and substantially co-axial with the scanning disc, 5 said viewing opening having two sides radial of said pivotal mounting, each side having a length substantially equal to twice the radial distance between successive turns of said spiral, and means for adjustably moving said member angularly about said pivotal mounting.
6. In a television receiver, the combination of a scanning disc having a series of openings the locus whereof is a spiral having a plurality of turns; a member having a viewing opening therethrough, and pivotally mounted adjacent to and substantially parallel and co-axial with the scanning disc, said viewing opening having two sides radial of said pivotal mounting, each side having a length exceeding the turn pitch of said spiral, and means for adjustably moving said member angularly about said pivotal mounting; a second member having a viewing opening therethrough mounted on said first-named member, two sides of said latter opening being substantially normal to a radius bisecting the opening through the first said member, the length of each of said two normal sides being substantially equal to the distance apart of successive openings in the scanning disc at the radius of each of said sides.
7. In a television receiver, the combination of a scanning disc having a series of openings the locus whereof is a spiral having a plurality of turns; a member having a viewing opening therethrough, and pivotally mounted adjacent to and substantially co-axial and parallel with the scanning disc, said viewing opening having two sides radial of said pivotal mounting, each side having a length exceeding the turn pitch of said spiral, a second member having a viewing opening therethrough and movably mounted on said first-named member, the opening in said second member having a radial length substantially equal to the turn pitch of the said spiral; means for adjusting said first member angularly about its pivotal mounting and a second means for adjusting said second member radially of the scanning disc.
8. In a television receiver, the combination of a scanning disc having a series of openings the locus whereof is a spiral having a plurality of turns; a member having a viewing opening therethrough, and pivotally mounted adjacent to and substantially co-axial and parallel with the scanning disc, said viewing opening having two sides radial of said pivotal mounting, each side having a length exceeding the turn pitch of said spiral.
9. In a television receiver, the combination of a scanning disc having a series of openings the locus whereof is a spiral having a plurality of turns; a member having a viewing opening therethrough, and pivotally mounted adjacent to and substantially co-axial and parallel with the scanning disc, said viewing opening having two sides radial of said pivotal mounting, each side having a length exceeding the turn pitch of said spiral, and a second member having a viewing opening therethrough movably mounted on said first-named member.
10. In a television receiver, the combination of a scanning disc having a series of openings the locus whereof is a spiral having a plurality of turns; a member having a viewing opening therethrough, and pivotally mounted adjacent to and substantially co-axial and parallel with the scanning disc, said viewing opening having two sides radial of said pivotal mounting, each side having a length exceeding the turn pitch of said spiral, and a second member having a viewing opening therethrough movably mounted on said first-named member, two sides of said latter opening subtending an angle on the scanning disc substantially equal to the angle subtended by successive openings in said disc.
11. In a television receiver, the combination of a scanning disc having a series of openings the locus whereof is a spiral having a plurality of turns; a member having a viewing opening therethrough, and pivotally mounted adjacent to and substantially co-axial and parallel with the scanning disc, said viewing opening having two sides radial of said pivotal mounting, each side having a length exceeding the turn pitch of said spiral, and a second member having a viewing opening therethrough movably mounted on said first-named member, two sides of said latter opening subtending an angle on the scanning disc substantially equal to the angle subtended by successive openings in said disc, and a light source attached to said second member.
12. In a television receiver, the combination of a scanning disc having a series of openings the locus whereof is a spiral having a plurality of turns; a member having a viewing opening therethrough, and pivotally mounted adjacent to and substantially co-axial and parallel with the scanning disc, said viewing opening having two sides radial of said pivotal mounting, each side having a length exceeding the turn pitch of said spiral, and a second member having a viewing opening therethrough movably mounted on said first-named member, two sides of said latter opening subtending an angle on the scanning disc substantially equal to the angle subtended by successive openings in said disc, and a light source attached to said second member.
13. In a television receiver, the combination of a scanning disc having a series of openings the locus whereof is a spiral having a plurality of turns; a member having a viewing opening therethrough, and pivotally mounted adjacent to and substantially co-axial and parallel with the scanning disc, said viewing opening having two sides radial of said pivotal mounting, each side having a length exceeding the turn pitch of said spiral, and a second member having a viewing opening therethrough movably mounted on said first-named member, two sides of said latter opening subtending an angle on the scanning disc substantially equal to the angle subtended by successive openings in said disc; means for adjusting said first member angularly about its pivotal mounting and a second means for adjusting said second member radially of the scanning disc.
14. In a television receiver, the combination of a scanning disc, a source of modulated light, a movably mounted member having a viewing opening whereof two sides are radial to the centre of said disc, a second member movably mounted on said first member and having a viewing opening and independent means for moving each of said movable members.
